UNITED STATES PATENT OFFICE

158,112

GAME DEVICE

Maurice Marks, Westport, Conn.

Application July 10, 1947, Serial No. 140,207

Term of patent 7 years

(Cl. D34—5)

To all whom it may concern:

Be it known that I, Maurice Marks, a citizen of the United States of America, residing in Westport, county of Fairfield, and State of Connecticut, have invented a new, original, and ornamental Design for a Game Device, of which the following is a specification, reference being had to the accompanying drawing, forming part thereof.

Fig. 1 is a perspective view of a game device, showing my new design.

Fig. 2 is a fragmentary view of the back portion as shown in Figure 1.

I claim:

The ornamental design for a game device, substantially as shown and described.

MAURICE MARKS.
